PAPER FEED DEVICE

Benjamin Cooper, Jersey City, N. J.

Application February 14, 1941, Serial No. 378,847

10 Claims. (Cl. 271—2.4)

This invention relates to paper feed devices. It is particularly directed to registers, accounting, or calculating machines wherein a strip sheet is used for receiving the successive impressions of printing wheels as the strip is advanced.

The present invention may be readily adapted to a registering system for checking tolls over highways, bridges, or tunnels. In such a checking system accounting costs are materially reduced when an elongated strip sheet having a plurality of successive, preprinted ledger forms is used in the register. The preprinted forms are separated by transverse perforations and may be ruled off into columns with appropriate headings printed thereabove. The lower portion of the forms may bear suitable descriptive wording and blank spaces for the entry of totals, money collected, and collector's signature or number.

When a collector goes on duty, one of the preprinted forms is placed in printing position in the register. Most registers are provided with timing means to give an hourly print of the accumulated data of the register. Thus during the entire time a collector is on duty hourly prints are made on the form in the proper columns. When the collector goes off duty, the device hereinafter disclosed is actuated to advance the complete printed record of all transactions to position where the collector may sever the same from the strip sheet. The advance of the completed form by the hereinafter disclosed device will move into printing position another preprinted form for use during the next shift by another collector.

The data impressed form is taken by the collector and left at the administration office where the data is computed and the computations entered on the form. The forms may then be filed away in loose leaf binders as ledger books. Thus a separate and complete record is had of each collector, and the need for transferring data from recording tapes is entirely eliminated.

It is an object of this invention to provide a paper advance device having means to advance an elongated strip sheet of preprinted forms a predetermined distance so that a succeeding form of said sheet is brought into printing position while the impressed printed form is advanced to a position where it may be readily severed from the elongated sheet.

It is a further object of this invention to provide a paper feed device of the character described comprising mechanism controlled by means on the strip sheet of preprinted forms to limit the extent of advance of the elongated sheet.

It is another object of this invention to pro-

vide a paper feed device of the character described having means to advance the elongated sheet predetermined lengths under the control of an operator, and additional means under the control of the printing mechanism to automatically advance the sheet after each printing operation one line to permit a succeeding printing operation.

Still another object of this invention is to provide in a paper feed device of the character described means to prevent the advance of a preprinted form on said strip before said preprinted form receives at least one impression from the printing wheels.

15 Still a further object of this invention is to provide a highly improved, compact, and rugged device of the character described which shall be easy to operate, relatively inexpensive to manufacture, positive in action, which shall have a large variety of applications, and yet be practical and efficient to a high degree in use.

Other objects of this invention will in part be obvious and in part hereinafter pointed out.

The invention accordingly consists in features 25 of construction, combinations of elements, and arrangement of parts which will be exemplified in the construction hereinafter described, and of which the scope of application will be indicated in the following claims.

30 In the accompanying drawings, in which one of the various possible illustrative embodiments of this invention is shown,

Fig. 1 is a front elevational view of a device embodying the invention.

35 Fig. 2 is an end view of the device with a cap cover removed.

Fig. 3 is a cross-sectional view taken along the line 3—3 of Fig. 1.

Fig. 4 is a cross-sectional view taken along the line 4—4 of Fig. 1.

40 Fig. 5 is a schematic wiring diagram of the circuit controlling the paper advance mechanism.

Fig. 6 is a plan view of a recording tape showing the control openings.

45 Fig. 7 is a cross-sectional view taken along the line 7—7 of Fig. 1.

Referring now in detail to the drawings, 10 designates a register embodying the invention, comprising a frame 11 having two parallel side walls 12 and 13, and a horizontal base plate 14 fixed to said side walls above the lower edges thereof.

The side walls 12 and 13 are provided with through openings 15 at their upper edges to facilitate handling of the register 10. Integral with

the inner surface of side wall 13, and below the through opening 15 is a boss 16 having a vertical portion 17 and two horizontal strengthening ribs 18. Integral with the inner surface of side wall 12 and in horizontal alignment with boss 16, is a similar boss 19 having a vertical portion 20. For the purposes hereinafter described there is fixed to the vertical portions 17 and 20 of the bosses 16 and 19, as by screws 21, a mounting bar 22 disposed in a vertical plane whose upper and lower edges are parallel with the base plate 14.

Side wall 13 is further provided near its front edge with a through opening 23 and with a through opening 24, below and in alignment with the opening 23. Fixed in the through opening 23, as by screws 25, is a bearing 26. Fixed to the outer surface of said side wall as by screws 27, is a gear guard 28 concentric with the opening 23 and enclosing said opening and also the opening 24. Fixed to the inner surface of wall 12 is a bearing 29 in horizontal alignment with the bearing 26. Integral with the inner surface of side wall 12 is a stud pin 30, and a boss 31 (Figs. 1 and 4).

For the purposes hereinafter described, there is journaled in bearing 29, and through the bearing 26, a horizontal shaft 32, extending slightly beyond the gear guard 28. Fixed to said shaft, as by screws 33, at spaced intervals, are a plurality of knurled rollers 34. Fixed to said shaft near side wall 13, as by screws 35 is knurled roller 36, having a peripheral groove 37 about its center portion. Fixed to said shaft near side wall 12 is a ratchet wheel 38.

Fixed to the mounting bar 22, as by screws 39, are a plurality of shouldered members 40, each provided with two depending shoulders 41. Fixed in the lower ends of each pair of shoulders 41 are horizontal, concentric shafts 42. Rotatably mounted on each of said shafts are a plurality of digit printing wheels 43 adapted to be actuated by a pawl swing 44 to advance said digit wheels. The pawl swings are actuated by electromagnetic counters (not shown) such as disclosed in my patent for Electromagnetic counter units, No. 2,185,724, issued January 2, 1940.

Journalized in side walls 12 and 13, near the upper and rear edges of said walls is a horizontal shaft 52. Mounted on said shaft is a spool 53 carrying a paper roll 54 of recording paper P.

Fixed to the side walls 12 and 13 is a paper guide 55 carrying said paper downwardly and forwardly under the digit wheels 43 and over the knurled rollers 34. Fixed to the upper plate of said paper guide, adjacent to each of the side walls 12 and 13, and between each set of digit wheels 43, is a forwardly extending finger 55a supporting a printing ribbon R. The printing ribbon is carried underneath the digit printing wheels 43 and above the paper P, and over rollers 55b. The printing ribbon R is adapted to be advanced after each printing operation by a ribbon advancing mechanism (not shown) such as for example disclosed in my patent for Electromagnetic printing counters, No. 2,115,410, April 26, 1938.

The paper P is a strip or web divided into sections which may carry printed forms. Between the printed sections are transverse lines of perforations 92 to facilitate severing of said sections from strip proper. Each section is further provided with a marginal through opening 91, the openings 91 being in alignment (Fig. 6). The openings 91 may be in the form of longitudinal slots for the purpose hereinafter appearing.

Means is now provided to automatically advance the paper P a predetermined distance, the extent of advance being under the control of the paper itself.

There is further fixed on mounting bar 22, adjacent wall 13, as by screws 94, a bracket 93, provided with a depending shoulder 95. Pivot to the lower end of shoulder 95, as at 96, is a lever 97 having a forwardly extending arm 98, a rearwardly extending arm 99, and an upwardly extending arm 100. Arms 98 and 99 are provided with shoulder portions 101 and 102, respectively. Arm 100 is provided at its outer end with an insulated pin 107.

Fixed to shoulder 101 of arm 98, as by pin 103, is a roller 104 aligned with the peripheral groove 37 of the knurled roller 36, and adapted to ride over the surface of the paper P on a line with the through openings 91. Roller 104 is held against the surface of paper P by a light coil tension spring 105 connected at one end to shoulder 102 and at its other end to a pin 106 in member 93. Spring 105 is sufficiently charged to rotate lever 97 in a clockwise direction about the pivot 96 (Fig. 3) when an opening 91 in the paper P is moved under the roller 104, permitting roller 104 to engage the peripheral groove 37.

For the purpose hereinafter appearing there is fixed to member 93 two normally closed insulated spring fingers 108 and 109. Spring finger 109 is engaged by the insulated pin 107 and is adapted to be moved thereby out of engagement with spring finger 108 upon rotation of lever 97 in the manner hereinabove described, when the roller 104 drops through an opening 91 into groove 37.

Fixed to the outer end of shaft 32 is a ratchet 110. Rotatably mounted on said shaft between the wall 13 and gear guard 28 is a gear 111. Fixed thereto is a plate 112. Fixed to plate 112 is a boss 113 to which there is pivoted a pawl 114. Pawl 114 is adapted to engage the teeth of ratchet 110 and is held in engagement therewith by a torsion spring 115 mounted on said boss and fixed to said pawl and to said plate.

Fixed to the inner surface of wall 13, as by screws 116, is an electric motor 117, having a horizontal drive shaft 118, one end of which passes through the opening 24 in said wall, the other end extending toward side wall 12. Fixed to the end of said shaft adjacent to the outer surface of wall 13 is a pinion shaft 119 carrying a pinion 120 adapted to mesh with the teeth of gear 111. Fixed to the other end of shaft 118 adjacent to said motor is a metal washer 121. Rotatably mounted on said shaft are two fiber washers 122 having a star ratchet 123 interposed between them; and a metal washer 124. Fixed to the outer end of shaft 118, as by screw 125, is a metal washer 126. Placed about shaft 118 and abutting washers 126 and 124 is a coil compression spring 127 urging the washers 124 and 122 and the star ratchet 123 against the fixed washer 121.

Motor 117 is adapted to rotate its drive shaft in a clockwise direction, rotating pinion 120 in the same direction (Fig. 2). The gear 111 is thus rotated in a counterclockwise direction, rotating the plate 112 and its pawl 114. Pawl 114 will thus engage the teeth of ratchet 110, rotating said ratchet in a counterclockwise direction. Shaft 32 will thus be rotated in a counterclockwise direction to advance the paper P.

Fixed to motor 117, as by screws 128, is a vertical mounting plate 129. Fixed to said mounting plate, as by screws 131, is a horizontal support

133. Mounted on said support is a relay 134 having a coil 135 and an armature 136 pivoted to the support, as at 137. Fixed to and extending through said armature is an insulated pin 137. Mounted on the support 133 and extending upwardly therefrom are two pairs of normally closed insulated spring contact fingers 138 and 139; 140 and 141, the former finger being engaged by pin 137. Spring fingers 139 and 141 are interconnected at their outer ends by an insulated block 142 to move together. When armature 136 is in initial position, as shown in Fig. 3, pin 137 will hold spring fingers 138, 139, and 140, 141 open, permitting said fingers to close upon energization of the relay 134.

Pivoted to mounting plate 129, as at 143, in alignment with the star ratchet 123, is a pawl 144 having a depending arm 145, and an upwardly extending arm 146 adapted to engage a tooth of said star ratchet. Arm 145 is connected to mounting plate 129 by a coil tension spring 147 connected to a pin 148 in said plate, said spring urges pawl 144 to rotate in a counterclockwise direction about its pivot 143 (Fig. 3). Depending arm 145 abuts the insulated pin 137, and due to the action of spring 147 tends to rotate armature 136 in a clockwise direction about its pivot 137.

When pawl 144 is in its initial position (Fig. 3), arm 146 engages a tooth of star ratchet 123. Upon energizing relay 134, armature 136 rotates in a counterclockwise direction, rotating pawl 144 in a clockwise direction to release the star ratchet from said pawl. Upon deenergization of said relay, spring 147 will return pawl 144 and armature 136 to their initial condition, pawl 144 again engaging one of the teeth of the star ratchet 123.

Referring now to Fig. 5, motor 117 is connected at one terminal by wire 150 to plus power supply, and at the other terminal by wire 151 to the spring finger 140. Spring finger 141 is connected by wire 152 to minus power supply. Spring finger 138 is connected by wire 153 to one end of coil 135 of the relay 134 and by wires 153 and 154 to one terminal of a push-button 155, the other terminal of said push-button being connected by wire 156 to plus power supply. Spring finger 139 is connected by wire 157 to spring finger 109. Spring finger 108 is connected by wire 158 to wire 156 to plus power supply. Coil 135 of the relay 134 has one end connected by wire 154 to push-button 155 and the other end connected by wire 159 to minus power supply.

The operation of the automatic paper advance will now be described.

When push-button 155 is closed, relay 134 becomes energized, the circuit being from plus power supply through wire 156, push-button 155, wire 154, coil 135, wire 159, to minus power supply. Relay 134 closes its associated switches, switch 138-139 closing an energizing circuit for coil 135 to hold said relay energized after the push-button is released, the circuit being from minus power supply through wire 159, coil 135, wire 153, switch 138-139, wire 157, switch 108-109, wire 158 to plus power supply.

By closing switch 140-141, motor 117 is operated, the circuit being from plus power supply through wire 150, motor 117, wire 151, switch 140-141, wire 152 to minus power supply. In energizing relay 134, armature 136 will pivot pawl 144 in a clockwise direction, Fig. 3, to disengage said pawl from the star ratchet 123. Motor 117 will thus be able to rotate, rotating shaft 32 to advance the paper P in the manner hereinabove described.

In advancing the paper P, an opening 91 in said paper will slide under the roller 104 of the lever 97, permitting said roller to ride in the peripheral notch 37 of the knurled roller 36. Lever 97 will thus be rotated in a clockwise direction by its spring 105 (Fig. 3), opening the switch 108-109. By opening switch 108-109, the holding circuit for coil 135 is opened permitting relay 134 to become deenergized. Armature 136 of said relay will then be rotated in a clockwise direction about its pivot 137 by spring 147 (Fig. 3) to open the switches 138-139 and 140-141, while pawl 144 rotates in a counterclockwise direction to engage one of the teeth of star ratchet 123.

By opening switch 140-141, the electrical power to motor 117 is disconnected. Due to the inertia of the armature of said motor, shaft 118 will continue to rotate after the power has been shut off. This rotation is quickly checked by the engagement of pawl 144 and the star ratchet 123 and the friction generated between the fiber washer 122 and the metal washer 121 fixed to said shaft, the advance of the paper being halted as roller 104 reaches the end of opening 91.

While the paper advance mechanism herein disclosed has been shown as being operative by a push-button, a lock switch might easily be substituted for the said push-button, thus permitting the recording tape and its recorded data to be kept under lock and key; or a key identifier might be substituted for the said push-button such as disclosed in my application for a Key identifier, Serial Number 328,534, filed April 8, 1940, whereby the paper advance mechanism is actuated by the withdrawal of an identification key from the identifier.

Means is provided to print against the digit printing wheels 43.

To this end there is journaled in the side walls 40 and 43 a horizontal shaft 45. Fixed to said shaft are a plurality of printing hammers 46, one printing hammer being in alignment with each set of digit wheels 43, and adapted to strike against the same upon rotation of shaft 45, paper and ribbon being interposed in the manner hereinbefore described.

Fixed to base plate 14, as by screws 47, is a solenoid 48, having an armature 49. Fixed to shaft 45, and in alignment with armature 49 is an arm 50, connected by link 51 to the upper end of armature 49. Solenoid 48 may be energized by a timing device (not shown) to give periodic prints or it may be energized by a push-button or key in any of the well-known ways.

When solenoid 48 is energized armature 49 is moved downwardly, rotating arm 50 in a counterclockwise direction (Fig. 3). Shaft 45 is thus rotated in the same direction to rotate the printing hammers 46 against the printing wheels 43, the paper P and the ribbon R being interposed, to print on said paper.

Means is provided to automatically advance the paper P a line space after each printing operation.

To this end there is journaled in side walls 12 and 13, near the front edges thereof, a shaft 56 parallel to shaft 32 and slightly thereabove. Fixed to shaft 56 are a plurality of pressure members 57, one for each of the knurled rollers 34. Each of said pressure members comprises a yoke member 58 rotatably mounted on shaft 56, provided with two parallel arm 59 and 60, arm 60 being provided with a shoulder 61; and a crosspiece 62. Rotatably mounted in the ends of arms 59 and 60 is a roller 63 registering with a

knurled roller 34. Fixed to shaft 56 and between arms 59 and 60 is a dog 64 carrying a pin 65 adapted to be engaged by shoulder 61. Mounted on shaft 56 is a torsion spring 66, one end of said spring being fixed to pin 65 and the other end being fastened to crosspiece 62 (Fig. 7).

Torsion springs 66 tend to rotate pressure member 57 in a counterclockwise direction (Fig. 7) pressing rollers 63 downwardly on knurled roller 34 to hold the paper P, the pins 65 being free of shoulders 61.

Pivotly mounted on shaft 32, adjacent ratchet 38 is a pawl swing 67, having a depending arm 68. Pivotly mounted on arm 68, as at 69, is an actuating pawl 70, held in engagement with the teeth of ratchet 38 by a leaf spring 71. Pivotly mounted on boss 31 on side wall 12 is a stop pawl 72 held in engagement with the teeth of ratchet 38 by a torsion spring 73 mounted on said boss and fixed to said wall at one end and to said stop pawl at the other.

Fixed to shaft 45, in alignment with pawl swing 67, is an arm 74 carrying a pin 75, interconnected to frame 11 by a coil tension spring 76. The lower end of arm 74 is connected to the pawl swing 67 by link 77.

Each time solenoid 48 is energized to rotate shaft 45 for bringing the printing hammers 46 into printing position, arm 74 is rotated in a counterclockwise direction, Fig. 3, rotating the pawl swing 67 in the same direction. Ratchet 38 is held by the stop wall 72 thus permitting pawl 70 to slide over a tooth of said ratchet. After the printing operation, tension spring 76 rotates arm 74, and the printing hammers 46, in a clockwise direction to initial position. Pawl swing 67 is thus rotated in the same direction by link 77, the actuating pawl 70 engaging the ratchet wheel 38 and rotating it in a clockwise direction. Thus shaft 32 is rotated in the same direction, rotating the knurled rollers 34. Due to the pressure of rollers 63 on the knurled rollers 34 the paper P is moved one line space forward toward the front of the register 10.

Means is provided to release the pressure members 57 to free the paper P from the rollers 63 and the knurled rollers 34.

To this end there is fixed to shaft 56 adjacent wall 12, as by set screw 78, a lever arm 79, having a shoulder 80 adjacent wall 12 and a thumb plate 81 at its upper end. Pivoted to said arm adjacent wall 12, as at 82, is a bell crank 83 having an arm 84, provided with a notch 85; and an arm 86, provided with a pin 87. Bell crank 83 is further connected to arm 79 by a coil tension spring 88 connected to said bell crank and to said arm, as at 89.

When lever arm 79 is in normal position, pin 80 on wall 12 is engaged by notch 85, as shown in Fig. 4. To release the pressure members 57, bell crank 83 is rotated, by lifting pin 87 and rotating bell crank 83 in a counterclockwise direction about its pivot 82 to free notch 85 from the pin 80. Lever arm 79 may now be rotated in a counterclockwise direction (Fig. 4) until the shoulder of said arm engages a pin 90 in wall 12. Arm 79 will rotate shaft 56 in a counterclockwise direction, rotating the dogs 64 in the same direction. Pins 65 thus engage the shoulders 61 of arms 60, rotating the pressure members 57, to lift the rollers 63 from the knurled rollers 34.

Spring 88 will rotate the bell crank 83 in a clockwise direction about its pivot 82 (Fig. 4) thus bringing the lower edge of arm 84 in con-

tact with pin 80. Due to the pressure of said spring and the sloping edge of arm 84 lever arm 79 will remain in its release position with shoulder 80 engaging the pin 90. To reestablish pressure on the paper P and rollers 63, lever arm 79 is rotated in a clockwise direction (Fig. 4), arm 84 sliding over pin 80 until the pin again engages the notch 85.

It will be thus seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A paper feed device to advance a web having a plurality of openings, comprising a member having a portion adapted to ride on said web and to move into said openings when said openings register therewith, a motor, means operated by the motor to advance said web, a circuit for said motor, a normally open switch in said motor circuit, an electromagnet, a circuit for said electromagnet, said electromagnet being adapted to close the switch in the motor circuit when said electromagnet is energized, a normally open manual switch in the circuit for said electromagnet adapted to be closed to energize said circuit, a normally open switch in parallel with said manual switch adapted to be closed upon energizing said electromagnet, and a switch adapted to be opened by said member when said portion of said member moves into an opening in said web and connected in series with the last-mentioned normally open switch and in parallel with said manual switch.

2. A paper feed device to advance a web having a plurality of openings, comprising a member having a portion adapted to ride on said web and to move into said openings when said openings register therewith, a motor, means operated by the motor to advance said web, a circuit for said motor, a normally open switch in said motor circuit, an electromagnet, a circuit for said electromagnet, said electromagnet being adapted to close the switch in the motor circuit when said electromagnet is energized, a normally open manual switch in the circuit for said electromagnet adapted to be closed to energize said circuit, a normally open switch in parallel with said manual switch adapted to be closed upon energizing said electromagnet, a second switch in said second circuit adapted to be opened by said member when said portion of said member moves into an opening in said web, and connected in series circuit with said last-mentioned normally open switch and in parallel with said manual switch, brake means for said motor controlled by said electromagnet, and means to apply said brake to said motor upon deenergization of said electromagnet.

3. A paper feed device to advance a web having a plurality of openings comprising a member having a portion adapted to ride on said web and to move into said openings when said openings register therewith, a motor, a circuit for said motor, means operated by the motor to advance said web, an electromagnet, a circuit for said electromagnet, a switch in the circuit for said elec-

tromagnet controlled by said member, means controlled by said electromagnet to control the motor circuit, and a manual switch in parallel with the first switch to control the energization of said electromagnet.

4. A paper feed device to advance a web having a plurality of openings comprising a member having a portion adapted to ride on said web and to move into said openings when said openings register therewith, a motor, a circuit for said motor, means operated by the motor to advance said web, an electromagnet, a circuit for said electromagnet, a switch in the circuit for said electromagnet controlled by said member, means controlled by said electromagnet to control the motor circuit, a manual switch in parallel with the first switch to control the energization of said electromagnet, and brake means for said motor controlled by said electromagnet.

5. A paper feed device to advance a web having a plurality of openings, comprising a member having a portion adapted to ride on said web and to move into said openings when said openings register therewith, an electric motor, means operated by the motor to advance said web, an electromagnet, a circuit for said electromagnet, a switch in said circuit adapted to be actuated by said member when said portion of said member moves into an opening in said web, means controlled by said electromagnet to control the operation of the motor, and a second switch in series circuit with said first switch and controlled by said electromagnet.

6. A paper feed device to advance a web having a plurality of openings, comprising a member having a portion adapted to ride on said web and to move into said openings when said openings register therewith, an electric motor, means operated by the motor to advance said web, an electromagnet, a circuit for said electromagnet, a switch in said circuit adapted to be actuated by said member when said portion of said member moves into an opening in said web, means controlled by said electromagnet to control the operation of the motor, and a second switch in series circuit with said switch and controlled by said electromagnet, brake means for said motor controlled by said electromagnet, and means to apply said brake to said motor upon deenergizing said motor.

7. In combination, a motor, means operated by the motor to feed a web having openings at spaced intervals, manually actuated means to start the motor to advance said web, a member adapted to ride on the web and adapted to move through the openings, as said openings pass said member, means adapted to close the motor cir-

cuit when said member is out of said opening and riding on said web, and to open the circuit when said member moves through said openings to de-energize said motor, said last means including means to prevent the motor from again being energized if the said member moves out of said opening after moving into said opening, unless said manual means is again actuated.

8. In combination, a motor, means operated by the motor to feed a web having openings at spaced intervals, manually actuated means to start the motor to advance said web, a member adapted to ride on the web and adapted to move through the openings, as said openings pass said member, means adapted to close the motor circuit when said member is out of said opening and riding on said web, and to open the circuit when said member moves through said openings to de-energize said motor, said last means including means to prevent the motor from again being energized if the said member moves out of said opening after moving into said opening, unless said manual means is again actuated, a brake, and means to apply said brake to said motor automatically upon deenergizing said motor.

9. In combination, means to longitudinally advance a web formed with longitudinally spaced openings, a motor for operating said advancing means, an electromagnet, means controlled by said electromagnet to energize said motor, manually controlled means to energize said electromagnet, a member adapted to ride on the web, and move through the openings in said web, means controlled by said member to energize said electromagnet when said member rides on said web and deenergize said electromagnet when said member moves through said opening, said last means including means to prevent energization of said electromagnet should said member move out of said opening after moving into said opening unless said manual means is actuated.

10. A paper feed device to advance a web, having a plurality of openings, comprising a member having a portion adapted to ride on said web and to move into said openings when said openings register therewith, an electric motor, means operated by the motor to advance said web, means to deenergize said motor upon said portion moving through said motor openings, means to energize said motor after said motor has become deenergized upon said portion of said member moving into said opening, and while said portion is still in said opening, said last means including means to prevent the motor from again becoming energized upon said portion of said member riding out of said opening and onto the web.

BENJAMIN COOPER.
